UNITED STATES PATENT OFFICE.

SAMUEL HY. CROCKER, OF LONDON, ENGLAND.

DESIGN FOR A PAPER-FASTENER.

SPECIFICATION forming part of Design No. 24,633, dated August 27, 1895.

Application filed April 10, 1895. Serial No. 545,247. Term of patent 14 years.

To all whom it may concern:

Be it known that I, SAMUEL HENRY CROCKER, a subject of the Queen of Great Britain, and a resident of London, England, have invented and produced a new and original Design for Paper-Fasteners, of which the following is a specification, reference being had to the accompanying drawings.

My design for a paper-fastener is shown in the accompanying drawings, in which—

Figure 1 is a plan view, and Fig. 2 is a side view, of the fastener.

The fastener is two-armed in form, the arms being arranged at an acute angle with each other. The surface of one arm is ornamented by a rounded bead or teat projecting therefrom, while the surface configuration of the

other arm is modified by having a spur projecting therefrom.

The leading feature of the design consists in the two arms arranged at an angle to each other, one having a rounded head thereon and the other the projecting spur.

I claim—

The design for a paper fastener herein shown and described.

In witness whereof I have set my hand, this 4th day of February, 1895, in presence of two witnesses.

SAML. HY. CROCKER.

Witnesses:

FRANK WILLIAM PATTISON,
ALBERT EDWARD ELLEN.
